H. J. BROWNE,
ACETYLENE LAMP.
APPLICATION FILED MAY 22, 1918.

Patented Nov. 30, 1920.

UNITED STATES PATENT OFFICE.

HERBERT J. BROWNE, OF WASHINGTON, DISTRICT OF COLUMBIA.

ACETYLENE-LAMP.

1,360,878.

Specification of Letters Patent. Patented Nov. 30, 1920.

Application filed May 22, 1918. Serial No. 236,057.

To all whom it may concern:

Be it known that I, HERBERT J. BROWNE, a citizen of the United States, residing at Washington, in the District of Columbia, have invented certain new and useful Improvements in Acetylene-Lamps, of which the following is a specification.

The present invention has as its objective the provision of a simple illuminating device of the gas generating type designed particularly for service in trenches, dug-outs, camp quarters or the like, its utility, however, not being necessarily confined to such.

It is of the essence of this invention that the device possess simplicity of construction and be one which from the manufacturing standpoint may be cheaply made, yet at the same time one which shall be positive in action to afford a suitable illumination of the desired intensity as well as one readily cared for by the user. To this end the invention embodies a container so arranged or constructed as to provide for gas generation and supply to a suitable burner upon the commingling of the proper gas-forming substances, the action being quite automatic throughout.

As regards novel characteristics, it may be noted that since carbid is employed as the medium of gas formation, I provide for the automatic feed of water to the supply of this substance in such manner that the gas pressure will adequately care for the proper flow of the water in the proportion required for the maintenance of the gas supply as the latter is used; and, secondly, I provide means so controlling the gas generation as to insure that the illumination will be steady or non-fluctuating; and, lastly, I provide an assemblage of parts enabling the parts to be easily cleaned and replenished as to the gas-forming substances referred to.

These and such other objects as may hereinafter appear are attained by the novel construction, combination and arrangement of parts to be hereinafter specifically described and claimed. Reference will now be had to the accompanying drawings forming a part of this specification, wherein:

Figure 1 is a vertical sectional view of an apparatus constructed in accordance with my invention;

Figs. 2 and 3 are horizontal sectional views on the respective lines 2—2, 3—3 of Fig. 1;

Fig. 4 is a sectional view on the line 4—4 of Fig. 1, and showing more clearly the interlocking connection between the inner receptacle sections; and

Fig. 5 is a fragmentary detail view showing the formation of the flange element of the interlocking means between the inner and outer receptacles.

Referring to the drawing, 1 indicates an outer receptacle of any desired shape and size but preferably provided at one side with a suitable handle 2 which latter is formed with an aperture 3 by means of which the apparatus may be suspended from a wall or other support. This outer receptacle is adapted to contain a suitable supply of water which surrounds an inner receptacle of relatively smaller diameter and consisting of the lower holding section 4 and the upper or covering section 5 of sleeve-like form loosely fitting over the said lower section. It should be observed that the space between these parts in the drawing is sufficient to admit a small quantity of water to stand therein to provide a liquid seal between these parts while the outer column similarly forms the liquid seal between the outer and inner containers 1 and 5.

As shown clearly in Fig. 1, the bottom of the outer receptacle is provided with small protuberances 6 preferably formed by pressing the metal of the bottom inwardly, these protuberances constituting a seat upon which the inner receptacle is disposed. The inner receptacle is held in proper position upon this seat by suitable interlocking means consisting in the embodiment herein disclosed of spaced angular pieces 7 attached to the outer receptacle about its mouth, and an annular flange 8 surrounding the upper portion of the covering section 5 of the inner receptacle. This flange is notched as indicated at 9 so that the angular pieces 7 will pass therethrough and beneath the flange when the inner receptacle is positioned in operative relation within the outer container. Furthermore the flange, as indicated at 8', is preferably stamped on an incline so as to obtain the necessary friction between the interlocking connection which will prevent accidental displacement of the parts in use.

Any other suitable interlocking connection may be employed in lieu of this just described. In addition to the foregoing the inner receptacle sections are preferably connected by a bayonet slot and pin arrange-

ment indicated at 10 and shown most clearly in Fig. 4 of the drawing.

The inner receptacle is provided with a conical feed passage 11 which extends upwardly within the same so as to bring the feed aperture 12 establishing communication between the outer receptacle and the inner receptacle at a suitable height above the bottom of the latter. The carbide which is utilized for generating the gas for this apparatus is disposed within the inner receptacle and about this conical portion. The amount of carbide which is utilized is preferably not greater than will be sufficient for supplying gas a predetermined period, it being important that the height of the carbide shall not extend above the feed aperture 12 in order to prevent clogging of the latter. This conical portion 11 constitutes a support preferably of an absorbent member 13, washer-like in form and consisting preferably of felt. This member lies over the carbide and receives the water from the feed aperture so as to evenly distribute the liquid to the carbide. This is an important feature of my invention because it constitutes a means for regulating the generation of the gas in a steady consistent manner so that the supply will be such as to eliminate fluctuation at the burner. The felt member furthermore, constitutes a strainer and a cooling medium for the gases, these devices being more effective when the gas is thus cooled.

At the top the inner receptacle is provided with an outlet 14 to receive the gas burner 15 which in turn carries a suitable chimney 16 preferably of non-breakable character such as mica.

It will be apparent from the foregoing that the apparatus described is made up of relatively few parts, may be cheaply manufactured for this reason and yet will afford an entirely adequate source of illumination for rough service such as is met with in the places hereinbefore referred to. In the use of the apparatus it is only necessary to introduce a suitable amount of water into the outer container, whereupon the inner receptacle having the carbide previously supplied thereinto is disposed in proper position within the outer receptacle and locked in place against displacement. The water capacity of the receptacle is such as to always insure a proper degree of hydrostatic pressure above the required minimum for the automatic feed during the predetermined working period of operation so that the gas generation will remain at highest point of efficiency throughout its use. Thus hydrostatic and atmospheric pressure upon the fluid column will act to feed the liquid into the inner receptacle through the feed aperture 12 and the formation of the gas in the gas chamber of

the inner receptacle will proceed, the back pressure of said gas acting through aperture 12 and on the water column between the inner receptacle parts 4 and 5 being the controlling means affecting the flow of the liquid into the gas generating chamber. It should be here noted that the arrangement and formation of the passage 11 such that it projects into the inner container to a point above the carbide, and into the gas space of said container, with the single feed aperture, is important. In other words this construction insures first that the water will not feed to the carbide except through the aperture 12 which is directly exposed to the gas pressure and is thereby controlled by said pressure; that second, when the pressure in the gas space becomes equal to the hydrostatic pressure, the entrance of the water into the inner container is cut off immediately the water is pressed below this terminal of the passage so that the gas generation will cease before the production of fluctuation in the gas flame. With this construction, moreover, it is important to note the water will not be forced outwardly in the passage 11 to a point below the level of the bottom of the inner container, so that likelihood of escape of the gas through the liquid in the outer container is eliminated. The action is automatic and does not require any regulation on the part of the user of the apparatus to produce the desired result. Ignition of the gas supply at the burner tip will provide for the necessary illumination, and to facilitate the initial action of ignition any desired valve or petcock may be provided at the top of the parts to allow the air to be discharged from the gas chamber as the gas forms, such means not being illustrated as it is conventional in apparatus of this character. When the illumination is to be discontinued it is only necessary to remove the water from the outer receptacle or displace the inner carbide receptacle from the outer liquid container.

Having thus described my invention, what I claim as new is:

1. An illuminating device of the class described comprising a liquid holding container and a separate gas container adapted to receive a gas generating substance, one arranged within the other, said gas container having a feed aperture below the liquid level to provide a hydrostatic pressure column, said aperture being arranged in spaced relation to the gas generating substance so as to be exposed to the pressure of the gas in the gas chamber whereby the liquid will be fed to the gas generating substance in inverse proportion to the extent of the pressure in the gas chamber, and absorbent distributing means disposed in the gas chamber in contact with the gas gener-

ating substance and spaced from the aperture to permit regulation of the flow of the liquid from the aperture and to carry the liquid to the gas generating means.

5. 2. An illuminating device of the class described comprising a liquid holding container and a separate gas container adapted to receive a gas generating substance, one arranged within the other, said gas container having a feed aperture below the liquid level to admit the liquid into the same, and absorbent means intermediate the aperture and the gas generating substance and below the said aperture to receive the liquid and evenly distribute the same thereto, said means being so arranged as to completely cover the gas forming surface of the substance to insure passage through said means to the gas chamber, the flow of the 10 liquid to said means being controlled by the gas pressure in the gas chamber.

3. An illuminating device of the class described comprising a liquid holding container and a separate gas container adapted to receive a gas generating substance, said 15 gas container having at its lower portion a feed passage for the liquid which passage

extends into the gas generating chamber to a point above the gas generating substance an absorbent member arranged over the substance and so formed and arranged as to control the distribution of the liquid thereto and prevent direct passage of unstrained gas to the gas chamber, and a burner connected to said gas container.

4. An illuminating device of the class described comprising an outer receptacle for sustaining a liquid column, an inner receptacle having in its base portion a feed passage for admitting liquid into the inner receptacle under hydrostatic pressure, said passage projecting inwardly into the inner receptacle to a point above the gas forming substance disposed in the latter and having its feed aperture arranged in spaced relation to the bottom of said receptacle, said inner receptacle being adapted to receive the gas generating substance about the passage and below the feed aperture thereof, and a liquid distributing member supported 40 by said passage and completely covering the 45 gas generating substance.

In testimony whereof I affix my signature.
HERBERT J. BROWNE.
